UNITED STATES PATENT OFFICE.

JOHN W. HASBURG, OF CHICAGO, ILLINOIS.

PAINT-PACKAGE.

1,249,391.

Specification of Letters Patent.

Patented Dec. 11, 1917.

Application filed July 19, 1917. Serial No. 181,533.

To all whom it may concern:

Be it known that I, JOHN W. HASBURG, a citizen of the United States, residing at Chicago, in the county of Cook and State 5 of Illinois, have invented certain new and useful Improvements in Paint-Packages, of which the following is a specification.

My invention relates to improvements in paint packages and more particularly to 10 packages for the transportation and protection of paints or gold preparations such as are used by china-ware decorators, wherein the paint contains a volatile diluent and is deposited on a glass palette.

15 Among the objects of my invention are to provide a package of minimum expense and maximum convenience affording adequate protection to the palette-carried pigment when the container is closed either originally 20 or after partial use of the pigment, and enabling the package to be handled with satisfactory results with a minimum of care or attention on the part of the user.

These and other objects will become apparent to those skilled in the art I attain by 25 means of my invention which consists of the combination hereinafter shown and described as specified in the claims.

In the drawings, 30 Figure 1 is a perspective view showing the packaged stock.

Fig. 2 is a broken plan view; and

Fig. 3 is a section on line 3—3 of Fig. 2.

In a paint package embodying my invention I may employ the ordinary square glass palette 10 bearing on its upper surface a 35 paint deposit 11, such as commercial prepared gold, the gold being admixed with a volatile carrying agent or oil that gives to 40 the deposit a pasty or semi-solid consistency.

Such paint-paste bearing palettes are well known in the art, and it is equally well known that for commercial availability they 45 must be packaged in such fashion as to preserve the paint against rapid evaporation of its oil, maintain the deposit free from dust or other impurities, and secure it against contact with any portion of the 50 package in ordinary shipment or handling.

In so packaging I employ the customary paste-board box base 12 rectangular in outline and of a size suitable loosely to receive the palette 10, the side walls 12' extending

to a height above the palette greater than 55 the depth of the paint deposit 11.

The cover 13 of the package provides side walls 13' to telescope around the walls 12' of the base and the top web 13'' to complete the inclosure, the side walls 13' being preferably of height no greater than the walls 12', and having, preferably, finger notches 14, in opposite edge portions to give finger access to the box-base structure.

Upon the top structure is mounted a guard 65 15, comprising a peripheral wall 16, preferably circular in plan, depending from the flat portion of the top structure wholly in the space between the margin of the paint deposit 11 and the perimeter of the palette 70 10 and of such height as to bear firmly on the palette, thereby holding the two box elements from quite fully telescoping together, so that the top of the wall 12' is below the cover web 13'' while the side walls 75 13' of the cover are above the bottom plane of the box but preferably below the upper plane of the palette.

This guard may be variously constructed, the particular construction preferred and 80 shown affording the guard walls as part of a unitary circular cap, the flat web 17 of which is secured, as by a glue body 18, to the underside of the cover web, centrally of the cover. The inwardly presented surfaces of 85 the guard cap 15, and preferably its side wall edges, are coated with an impervious substance of a character not affected by the volatile oil of the pigments. To this end I 90 preferably employ a cellulosic coating, which may conveniently be applied by dissolving celluloid in a suitable volatile solvent as ether, and spraying, painting, dipping, or otherwise applying the pyroxylin enamel thus formed to coat the desired cap surfaces. 95 Such coating when dry adheres intimately to the pasteboard walls and forms smooth surfaces, impervious to water and to the vapors of the paint deposit.

In initial condition the two portions of 100 the package may be held together by sealing strip or strips 21, applied in any way to suit the taste of the maker.

It will be apparent that the construction of the guard cap in circular form is especially desirable. Not only does it give a fairly close investiture of the paint body, limiting the evaporation most desirably, but

also stiffens the cover element most effectually, preventing warping of the cover and maintaining its free, circular edge in a plane for accurate fitting contact with the surface 5 of the glass palette. The cap affords an adequate sealing effect to close the circular compartment containing the paint deposit, excluding dust and other impurities and retaining the volatile oils against and considerable evaporation.

Mechanically the construction offers many advantages in its cheapness, simplicity and ease of handling. When the package is open the single act of removing the covering exposes the paint deposit, but the latter is invariably closely covered and substantially re-sealed when the box is reclosed. Where it is desired completely to remove the paint-carrying palette this may be done without resorting to a knife or other implement for picking the glass plate out of the box bottom by inverting the box so that the palette rests upside down on the cap wall 15, and then lifting out the box bottom, exposing the edges of the glass palette to be grasped through the finger openings 14 in the box top. The glass cannot shift within the cover, when thus handled, so far as to foul the cap rim with the paint since the side 30 walls 13' permit of but comparatively little shifting of the palette while the latter rests on the cap rim. Other and further advantages will be apparent to those skilled in the art, and changes in the specific details of 35 construction may be made without departure from the spirit of my invention and within the scope of the appended claims.

Copies of this patent may be obtained for five cents each, by addressing the "Commissioner of Patents.
Washington, D. C."

Having described my invention, what I claim is:—

1. A paint package comprising a planar 40 palette centrally carrying a relatively thin paint deposit of plan dimensions materially smaller than the palette, a box bottom having side walls inclosing the palette, and a removable box top having a guard 45 rim to encompass the material body and contact throughout its perimeter with the palette between the margin of the latter and the paint deposit, the surfaces of said box top within the confines of said guard rim 50 bearing a coating impervious to the volatile component of the paint.

2. A paint package comprising a planar palette centrally carrying a relatively thin paint deposit of plan dimensions materially 55 smaller than the palette, a box bottom having side walls inclosing the palette, and a removable box top having a circular cap centrally secured thereto to encompass the material body and contact throughout its 60 perimeter with the palette between the margin of the latter and the paint deposit, the inner and edge surfaces of said cap within the celluloid-enamel bearing a coating rendering it impervious to the volatile component of the paint.

In testimony whereof I hereunto set my hand in the presence of two subscribing witnesses.

JOHN W. HASBURG.
